CIRCLE CUTTING MACHINE

William C. Dornbrook, Detroit, Mich.

Application May 2, 1941, Serial No. 391,553

4 Claims. (Cl. 164—71)

The present invention pertains to a novel machine for cutting circles or rings out of metal and is designed primarily for use by the printing industry.

In newspaper and other advertisements of a printed nature, printed circles are often used for ornamental and display effects. The printing character of the desired external and internal dimensions is often not at hand, and it is customary to make the character to order in the printing plant. The external and internal circumferences are scribed on a blank of type metal which is next roughly cut out along these circumferences and finally finished to size by filing. The operation does not warrant the installation of an expensive machine, and even in large newspaper plants, circular characters are made in the manner above described.

The object of this invention is to provide a simple and inexpensive machine for the purpose described, as well as one that is capable of cutting a double circle or more than one circle simultaneously. The machine consists essentially of a turntable on which the blank is secured, with a device for elevating the blank against one or more fixed cutting tools. It is evident that the machine herein described is not limited to the cutting of printing characters but is obviously suitable for cutting circles from various metals, wood and compositions for numerous purposes. The tools are however adjustable radially from the center of rotation of the turntable and are indexed along a fixed printer's scale. Preferably, the tool is not permitted to cut entirely through the blank and leaves a thinness of metal which enables breaking off the circle by hand.

The invention is fully disclosed by way of example in the following description and in the accompanying drawing in which:

Figure 1 is a vertical elevation of the device;
Figure 2 is a detail vertical section;

Figure 3 is a section on the line 3—3 of Figure 2;

Figure 4 is a section on the line 4—4 of Figure 1;

Figure 5 is a section on the line 5—5 of Figure 1 and,

Figure 6 is a section on the line 6—6 of Figure 1.

Reference to these views will now be made by use of like characters which are employed to designate corresponding parts throughout.

The machine is built in a frame 1 of appropriate construction in which is journaled a

vertical shaft 2. A motor 3 drives the shaft through a gear box 4.

On the upper end of the shaft 1 is splined a block 5 carrying a turntable 6. Beneath the block, a sleeve 7 is slidably mounted on shaft and receives a fork 8. From the fork is extended a lever 10 fulcrumed in the frame at 11 and extending beyond one side of the frame, as illustrated in Figures 1 and 4.

The frame 1 includes a pair of posts or uprights 9 at opposite sides of the turntable 6. The posts support a pair of rods 12 one above the other and crossing the projected axis of the shaft 2. The rods support one or more tool holders, each of which consists of a pair of blocks 13 adapted to be clamped on the rods by a screw 14. One of the blocks extends downwardly beyond the other and is adapted to receive a cutting tool 15.

Above the rods 12, the posts 11 support a bar 16 to which is secured a printer's scale 17 graduated in twelfths of an inch outwardly from the projected axis of the shaft 2.

The surface of the turntable 6 is formed with a suitable number of radial grooves 18 in which screw clamps 19 are mounted. A blank 20 of type metal is adapted to be secured between the clamps.

A bracket 21 is provided on the frame directly over the exposed end of the lever 10. This end is adapted to be engaged by a thumb screw 22 in the bracket 21, whereby the turntable 6 may be worked up and down at will through the fork 8 and sleeve 7.

The upper end of each pair of blocks 13 carries an index finger 23 in line with the tool 15 and adjacent to the scale 17. By this means, the tool is set at the desired distance from the center of rotation of the shaft 2 and turntable 6. It will be understood that the tool holder can be released for sliding on the rods 12 by means of the screw 14 and similarly tightened in place. The tool or tools not to be used are rendered idle by releasing the respective holders entirely from the rods 12 and setting them on the rods in a reverse position as shown in Figure 1.

In cutting the first circle out of the blank 20, it is preferable to use two tools set respectively at the internal and external radii for simultaneous cutting. During rotation of the turntable, the screw 22 is operated to bring the blank 20 against the tools in the manner previously described. The grooves cut by the tools are of such depth as to leave a thickness of metal from which the circle can be broken off

by hand. Any burrs remaining on the severed circle can readily be removed when they file. Additional circles can be cut out of the blank at the same time by using additional tools.

Although a specific embodiment of the invention has been illustrated and described, it will be understood that various alterations in the details of construction may be made without departing from the scope of the invention as indicated by the appended claims.

What I claim is:

1. A machine of the character described comprising a frame, a shaft journalled vertically therein, a turntable slidably carried by said shaft, a lever fulcrumed in said frame and adapted to impart vertical movement to said turntable during rotation of said shaft, means for supporting a work piece on said turntable, a horizontal rod supported in said frame over said turntable and passing substantially through the projected axis of said shaft, and a tool holder adjustably mounted on said rod. 15

2. A machine of the character described comprising a frame, a shaft journalled vertically therein, a turntable carried by said shaft, a lever fulcrumed in said frame and adapted to impart vertical movement to said turntable during rotation of said shaft, means for supporting a work piece on said turntable, a horizontal rod supported in said frame over said turntable and passing substantially through the projected axis of said shaft, and a tool holder 20

adjustably mounted on said rod, a scale mounted adjacent to said rod, and an indexing member on said holder and cooperating with said scale.

3. A machine of the character described comprising a frame, a shaft journalled vertically therein, a turntable carried by said shaft, a lever fulcrumed in said frame and adapted to impart vertical movement to said turntable during rotation of said shaft, a screw mounted in said frame and bearing against said lever to actuate the same, means for supporting a work piece on said turntable, a horizontal rod supported in said frame over said turntable and passing substantially through the projected axis of said shaft, and a tool holder adjustably mounted on said rod. 10

4. A machine of the character described comprising a frame, a shaft journalled vertically therein, a turntable carried by said shaft, a lever fulcrumed in said frame and adapted to impart vertical movement to said turntable during rotation of said shaft, a screw mounted in said frame and bearing against said lever to actuate the same, means for supporting a work piece on said turntable, a horizontal rod supported in said frame over said turntable and passing substantially through the projected axis of said shaft, and a tool holder adjustably mounted on said rod, a scale mounted adjacent to said rod, and an indexing member on said holder and cooperating with said scale. 25
